FIG. 1

FIG. 3

FIG. 2

FIG. 7

FIG. 4

FIG. 5

FIG. 6

FIGURE 1 is a perspective view of a combined nail clipper and pivotable blade tool showing my new design, with the pivotable blades shown in partially open position and the nail clipper lever in operating position;

FIGURE 2 is a front elevational view thereof with all blades and the lever in closed position;

FIGURE 3 is an elevational view taken from the left of FIGURE 2;

FIGURE 4 is an elevational view taken from the bottom of FIGURE 2;

FIGURE 5 is an elevational view taken from the rear of FIGURE 2;

FIGURE 6 is an elevational view taken from the top of FIGURE 2; and

FIGURE 7 is an elevational view taken from the right of FIGURE 2.

The essential features of my design reside in the portions shown in full line and particularly in the configuration of the slotted case and operating lever.

I claim:

The ornamental design for a combined nail clipper and pivotable blade tool, as shown and described.
